VENETIAN BLIND CORD LOCK

Hans K. Lorentzen, Montclair, N. J., assignor to
 Lorentzen Hardware Mfg. Corp., New York,
 N. Y., a corporation of New York

Original application August 17, 1940, Serial No.
 353,020. Divided and this application June 26,
 1942, Serial No. 448,589

6 Claims. (Cl. 156—17)

This invention relates to Venetian blind cord locks used for locking the elevator or lift cords of Venetian blinds. Originally the subject-matter was presented in my application Serial No. 353,020, filed August 17, 1940, of which this is a division.

General objects of the invention are to provide a Venetian blind cord lock of increased simplicity, to lower the manufacturing cost of such cord locks, to eliminate certain manufacturing operations in connection with such cord locks, and to improve the operating characteristics of the cord locks.

Various other and specific objects of the invention will be apparent to those skilled in the art from the following disclosure.

Fig. 1 of the drawing is a fragmentary front elevation showing the present invention in conjunction with a Venetian blind.

Fig. 2 is a vertical section taken approximately on the line 2—2 of Fig. 1, certain parts being omitted.

Fig. 3 is a fragmentary sectional view taken in general on the line 3—3 of Fig. 2.

Fig. 4 is a perspective view of the locking dog.

The cord lock is included in a combination cord lock and tilt bar bracket 10. This bracket is attached to the head-bar 7 in a well-known manner, and has a depending leg 16 which rotatably supports the gudgeon pin 15 that projects from the end of the tilt bar 12. Suspended from the tilt bar in a conventional manner are the conventional articulated slats 17 of the blind; and conventionally arranged lift cords 18 and 19 are provided for raising and lowering the blind.

The cord lock includes a stamped U-shaped sheet-metal casing 45 of a general form which is already known. The mouth of the U-formation is provided with integral projections which pass through openings in brackets 16 and are riveted thereto, e. g. at 3 in Fig. 3. Each side of the U-formation is provided with a wedge-shaped cut-out or notch such as shown at 46 in Fig. 3. A locking dog 47 is provided with a toothed edge 4 and is arranged to rock in the casing 45 to thereby lock and release the cords 18 and 19. Projecting laterally from both sides of locking dog 47 are flat extensions 48, 48 best seen in Fig. 4. In assembly, these extensions 48, 48 are inserted in notches 46 and then the U-shaped casing is assembled with and secured to the bracket 16. Thus the bracket 16 acts as a bridge member to close the notches 46 and keep the dog 47 in assembled position.

It will be noted that the flat extensions 48, 48 fit loosely into the notches 46 so as to permit rocking movement of the dog 47. With the cord swung against the teeth at 4 on the lower edge of the dog, slight upward movement of the cord rocks the dog upwardly and causes the cord to be wedged against the bump 5 in the casing 45 and to lock the cord in a manner well understood in the art. With the dog 47 in locking position, a slight downward pull on the cords 18 and 19 causes the dog to be released and to drop into the position shown in Fig. 3. The dog 47 may be a simple sheet metal stamping made in one operation and having integral therewith the teeth at 4 and the flat extensions 48, 48. The size and dimensions of wedge-shaped notches 46, 46 are so proportioned with respect to the flat extensions 48 that the notches cooperate with the extensions to arrest the dog at the desired stage of its downward or released movement. This arrested position is shown in Fig. 3.

The present invention is in some respects an improvement upon the cord lock shown in Lorentzen Patent 2,075,214 of March 30, 1937, and reference may be had to that patent for a more complete disclosure of certain structural features ancillary to the present invention.

In compliance with the patent statutes, I have disclosed the best form in which I have contemplated applying my invention, but it will be understood that the disclosure is illustrative of the invention rather than limiting the scope of the same.

35 What I claim is:

1. In a Venetian blind fitting of the type in which a U-shaped cord lock casing has a locking dog rockably mounted therein and has the mouth of the U-formation secured to a tilt bar bracket, the improvement which comprises: the locking dog being provided with integral extensions on which it rocks, the opposite sides of the U-formation being provided with notches into which the extensions are inserted, and said bracket acting to close the ends of said notches and thereby hold the dog in assembled position in the U-shaped casing.

2. In a Venetian blind fitting of the type in which a U-shaped cord lock casing has a locking dog rockably mounted therein and has the mouth of the U-formation secured to a tilt bar bracket, the improvement which comprises: the locking dog being provided with integral flat extensions on which it rocks, the opposite sides of the U-formation being provided with notches of wedge-

shaped form into which the extensions are inserted, and said bracket acting to close the ends of said notches and thereby hold the dog in assembled position in the U-shaped casing.

3. In a Venetian blind fitting of the type in which a hollow cord lock casing has a locking dog rockably mounted therein to move in cord-engaging and cord-release directions, the improvement which comprises: the locking dog being provided with extensions on which it rocks, and the casing being provided with cut-outs which loosely receive the extensions and act in conjunction therewith to limit the movement of the dog in cord-release direction.

4. In a Venetian blind fitting of the type in which a hollow cord lock casing has a locking dog rockably mounted therein to move in cord-engaging and cord-release directions, the improvement which comprises: the locking dog being provided with flat integral extensions on which it rocks, and the casing being provided with wedge-shaped cut-outs which loosely receive the extensions and act in conjunction with the edges of the extensions to limit the movement of the dog in cord-release direction.

5. In a Venetian blind fitting of the type in which a U-shaped cord lock casing has a locking dog rockably mounted therein and has the mouth of the U-formation traversed by a bridge member, the improvement which comprises: the locking dog being provided with extensions on which it rocks, the opposite sides of the U-formation being provided with notches into which the extensions are inserted, and said bridge member acting to close the ends of said notches and thereby hold the dog in assembled position in the U-shaped casing.

6. In a Venetian blind fitting of the type in which a U-shaped cord lock casing has a locking dog rockably mounted therein and has the mouth of the U-formation secured to a tilt bar bracket, the improvement which comprises: the locking dog being provided with extensions on which it rocks, the opposite sides of the U-formation being provided with spaces into which the said extensions are laterally inserted, and said bracket cooperating with the dog to hold it in assembled position in said U-shaped casing.
